RADIATOR

Paxson Winsborough, Pittsburgh, and Archibald H. Davis, Jr., New Castle, Pa., assignors to Shaw-Perkins Manufacturing Company, Pittsburgh, Pa., a corporation of Pennsylvania

Application August 4, 1936, Serial No. 94,208

10 Claims. (Cl. 257—149)

This invention relates to radiators, and more particularly to those in which parallel sheet metal plates are mounted in heat-exchanging relation on a tube through which a heating medium flows.

5 It is among the objects of this invention to provide such a radiator in which the tube is permitted to freely expand, in which stresses due to expansion and contraction of the pipe lines connected to the radiator are transmitted directly 10 to the radiator as a whole, and in which the edges and corners of the plates are protected against damage. Other objects include obtaining maximum radiation and air circulation for given weight, and great efficiency for a radiator of given 15 over-all dimensions.

In accordance with this invention a plurality of plates are disposed in fixed spaced relation, and disposed between each pair of them is a group of spaced floating plates which are shorter 20 and narrower than the fixed plates. A tube for conveying a heating medium through the radiator extends in a tortuous path through openings in all the plates, which are rigidly mounted on and in intimate contact with the tube, so as to 25 conduct heat away from it rapidly. At each end of the unit there is a heavier end plate, to which a pipe coupling is rigidly secured. The ends of the heating tube are securely connected to these couplings, but the end plate openings, through 30 which the intermediate portion of the tube extends, are enlarged to allow for axial and transverse movement of the tube caused by expansion and contraction. The edges of the fixed plates that project outwardly beyond the floating plates 35 tend to protect the radiator and in turn are protected by transversely curved members, preferably tubing surrounding the fixed plates.

The preferred embodiment of the invention is illustrated in the accompanying drawing in which 40 Fig. 1 is a side elevation of our radiator; Fig. 2 is a plan view thereof; Fig. 3 is an end view; Fig. 4 is a vertical transverse section taken on the line IV—IV of Fig. 1; Fig. 5 is an enlarged fragmentary longitudinal section taken on the line V—V 45 of Fig. 3; and Fig. 6 is an enlarged fragmentary horizontal section taken on the line VI—VI of Fig. 5.

Referring to the drawing, Figs. 5 and 6 in particular, a plurality of plates 1 are shown spaced 50 apart in fixed parallel relation by transversely curved spacer bars 2 disposed between the plates adjacent their corners. These plates and spacer bars are bound together into a substantially rigid unit by means of tie rods 3 that extend through 55 apertures in the corner portions of the plates be-

hind the bars. Disposed between each pair of fixed plates 1 is a group of spaced parallel plates 4, referred to herein as "floating" because they are not held in fixed position by the spacer bars, although their corner portions are provided with 5 apertures through which the tie rods extend. These floating plates are slightly shorter and narrower than the fixed plates, and their corners are disposed behind and shielded by the spacer bars.

The plates are provided with rows of aligned 10 openings through which a tube 6, adapted to convey a heating medium through the radiator, extends back and forth in a tortuous path as shown in Fig. 1. Preferably, the tube is formed of long, 15 horizontal sections connected at their ends by vertical bends 7, and the two opposite ends of the tube are advantageously disposed at diagonally opposite corners of the radiator. To insure rapid and efficient heat transfer from this tube to the various plates, the latter are tightly mounted 20 on the tube. A convenient way of connecting the tube and plates is to subject the tube to sufficient hydraulic pressure to expand it into tight 25 engagement with the flanged walls of the plate openings through which it passes. The flanges 25 on the plate opening give greater contact area and strengthen the whole structure.

To strengthen the entire radiator structure, an end plate 8 is disposed at each end of the unit as shown in Figs. 4, 5 and 6, preferably against 30 the outer face of one of the fixed plates 1, where it forms a rigid anchor for the tie rods. The end plates are thicker, and therefore more rigid, than the other plates, and may be further strengthened by providing them with laterally 35 projecting side flanges 9 throughout their central portion. Portions of the end plates are entirely flat and are provided with apertures for receiving the ends of the tie rods. Rigidly connected to each end plate around the end of tube 40 6 projecting therethrough, as by screws 11, is a pipe coupling 12 the inner end of which is tightly connected to the tube end and the outer end of which is threaded for connection to the heating system pipe line, not shown. Consequently, any 45 strains due to expansion or contraction of the latter are transmitted through the fitting directly to the heavy end plate and into the radiator as a whole, particularly tie rods 3, rather than to the tube alone.

Openings 13, in the end plates and the adjoining fixed plates 1, through which extends the portion of the tube intermediate its anchored ends, are larger than the tube. See Fig. 5. As a result, the tube floats in these openings and moves 55

back and forth in them as its horizontal sections expand and contract, and moves sideways in them as the bends 7 expand and contract. To protect the tube and prevent it from wearing, it is preferably encircled by collars 14 in openings 13.

At the outer end of each coupling 12 is a cover plate 16 of the same size as fixed plates 1. This plate is supported by extensions of the tie rods which project therethrough and carry nuts 17 that draw it up tight against a pair of rigid side sheets 18 that are thereby clamped between it and the fixed plate adjoining the end plate. The cover plate is preferably reinforced by a backing plate 19 of the same size as the floating plates, 15 the backing plate and adjacent end plates forming a support for the side sheets.

The projecting edges of fixed plates 1 and cover plate 16 tend to protect the floating plates by preventing objects from coming in contact with them, and those projecting edges are in turn protected by longitudinally split tubing 21 telescoped thereover to enclose them. This tubing likewise prevents the rather sharp edges of the plates from injuring anyone or anything coming in contact with the radiator, and it also improves the appearance of the radiator.

A radiator constructed in accordance with this invention is pleasing in appearance and protected from injury by objects that may strike it. It is highly efficient in heating qualities, since it permits free circulation of air over all radiating and heat-conductive surfaces. It has comparatively great surface exposure per unit of weight and over-all dimensions. Its structure allows for expansion and contraction without injury to itself because a large number of the conductor plates float with the heating tube the intermediate portion of which floats in the fixed end plates. Strains due to expansion and contraction of the heating system pipe line that might otherwise be transmitted directly to the heating tube and injure it, are transmitted directly to the radiator as a whole because the pipe couplings are rigidly connected to the end plates of the radiator.

According to the provisions of the patent statutes, we have explained the principle and construction of our invention, and have illustrated and described what we now consider to represent its best embodiment. However, we desire to have it understood that, within the scope of the appended claims, the invention may be practiced otherwise than as specifically illustrated and described.

We claim:

1. A radiator comprising a plurality of spaced fixed plates, bars disposed between the plates and engaging them adjacent their corners for maintaining them in spaced relation, tie rods extending through the plates for binding the plates and bars into a unit, a plurality of spaced floating plates disposed between each pair of said fixed plates, all of the plates being provided with openings therethrough, and a tube for conveying a heating medium extending through said openings in engagement with the plates.

2. A radiator comprising a plurality of spaced substantially parallel fixed plates, bars disposed between the plates and engaging them adjacent their corners for maintaining them in spaced relation, tie rods extending through the plates for binding the plates and bars into a unit, a plurality of spaced substantially parallel floating plates disposed between each pair of said fixed plates, all of the plates being provided with openings, a tube extending through said openings in engagement with the plates,

engagement with the plates, said fixed plates projecting outwardly beyond said floating plates, and transversely curved members connected to the edges of said fixed plates.

3. A radiator comprising a plurality of spaced parallel fixed plates, bars disposed between the plates and engaging them adjacent their corners for maintaining them in spaced relation, tie rods extending through the plates for binding the plates and bars into a unit, a plurality of spaced parallel floating plates disposed between each pair of said fixed plates, all of the plates being provided with openings, a tube extending through said openings in engagement with the plates, said fixed plates projecting outwardly beyond said floating plates, and a longitudinally split tube surrounding each of said fixed plates and enclosing the edges thereof.

4. A radiator comprising a plurality of spaced fixed plates, a plurality of spaced floating plates disposed between each pair of fixed plates, all of the plates being provided with openings, a tube extending through said openings in engagement with the plates, said fixed plates projecting outwardly beyond said floating plates, bars extending transversely of said floating plates and engaging said fixed plates adjacent their corners for maintaining them in spaced relation, and tie rods extending through all of the plates for binding the plates and bars into a unit.

5. A radiator comprising a plurality of spaced fixed plates, bars disposed between the plates and engaging them adjacent their corners for maintaining them in spaced relation, an end plate disposed at one end of the unit thus formed, tie rods extending through all of the plates for binding the plates and bars into a unit, a plurality of spaced floating plates disposed between each pair of said fixed plates, all of the plates being provided with openings therethrough, a tube extending through said openings in engagement with the plates, and a pipe coupling rigidly secured to said end plate and the end of said tube associated therewith.

6. A radiator comprising a pair of spaced end plates, a plurality of spaced substantially parallel plates disposed between the end plates, means for binding all of the plates into a unit, all of the plates being provided with openings therethrough, a heating tube extending through said openings in engagement with the plates and with its ends firmly attached to the two end plates, and a pipe coupling rigidly secured to each of said end plates and the end of the tube associated therewith.

7. A radiator comprising a pair of spaced end plates, a plurality of spaced parallel plates disposed between the end plates, each end plate having laterally projecting side flanges, means for spacing the plates apart, tie rods extending through all of the plates for binding them into a unit all of the plates being provided with openings therethrough, a tube extending through said openings in engagement with the plates and with its ends associated with the two end plates, and a pipe coupling rigidly secured to each of said end plates and the end of the tube associated therewith.

8. A radiator comprising a pair of spaced end plates, a plurality of spaced plates disposed between the end plates, tie rods extending through all of the plates for binding them into a unit, all of the plates being provided with openings therethrough, a heating tube extending through said openings in engagement with the plates, a

- pipe coupling rigidly secured to one of said end plates and the end of said tube associated therewith, a cover plate disposed at the outer end of said coupling, and a side sheet between said
- 5 cover plate and said end plate, said tie rods extending outwardly through the cover plate for holding it in position.
9. A radiator comprising a plurality of spaced fixed plates, bars disposed between the plates and 10 engaging them adjacent their corners for maintaining them in spaced relation, an end plate disposed at each end of the unit thus formed, tie rods extending through all of the plates for binding the plates and bars into a substantially rigid 15 unit, a plurality of spaced floating plates disposed between each pair of said fixed plates, all of the plates being provided with rows of flanged openings therethrough, and a heating tube extending through said openings in engagement 20 with said fixed and floating plates and with its ends rigidly secured to said end plates, said tube extending back and forth in said unit with its intermediate portion passing through openings in the end plates, said openings being larger than said tube to allow for expansion of the tube therein.
10. A radiator comprising a pair of spaced end plates, a plurality of spaced substantially parallel plates disposed between the end plates, means for binding all of the plates into a unit, all of the plates being provided with rows of openings therethrough, a heating tube extending through said 10 openings with its ends rigidly secured to said end plates, said tube extending back and forth in said unit in direct heat-exchanging relation with said plates, the openings in the end plates through which the central portion of the tube 15 extends being materially larger than the tube, and a collar rigidly mounted on the tube in each of said large openings, the collar being materially smaller than the opening.
